UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING MACHINE.

1,415,750.

Specification of Letters Patent.

Patented May 9, 1922.

Application filed June 4, 1921. Serial No. 475,060.

To all whom it may concern:

Be it known that I, JOHN A. WHERRY, a citizen of the United States, residing in New Orleans, in the parish of Orleans and State 5 of Louisiana, have invented certain new and useful Improvements in Typewriting Machines, of which the following is a specification.

This invention relates to a collating device for typewriting machines, and is in the nature of improvements which may be used with the device set forth in my prior Patent No. 1,351,081, granted August 31, 1920, and provides means whereby a plurality of work-sheets may be readily assembled with carbon sheets and rapidly adjusted in position. For this purpose, the collating device, comprising a collating table, is pivotally mounted on the carriage at the front of the platen, 10 and is swingable from a normally vertical position to a horizontal position, in which latter position the various carbon-sheets and work-sheets may be more easily adjusted and assembled. The platen is carried by the collating device, and is disconnected from the platen-rotating mechanism when the collating device is swung to horizontal position. When the work-sheets and carbon-sheets have been adjusted on the collating table, the 15 device is swung back to vertical position, the platen being again connected to the platen-rotating mechanism. The carbon-sheets are of a length sufficient to extend from the rear of the platen to the upper part 20 of the collating table, where the ends of the carbon-sheets are fixed in a clamp slideable lengthwise of the table. When the table is in a horizontal position, the clamp is slid upwardly on the collating table and the work-sheets are inserted between the carbon-sheets. The collating device is swung to vertical position at the front of the platen to connect the platen to the platen-rotating mechanism, and the various sheets are drawn 25 downwardly and rearwardly to the first line to be typed. When the work-sheets have been fully typed, the collating device is swung to horizontal position, and the process described above is repeated.

50 The carbon-sheets remain in the machine until worn out. Hitherto, these sheets have been short strips, which were removed from the machine when exhausted, and new sheets inserted. A feature of this invention is the 55 provision of a mounting for carbon-strips

wound upon rolls and supply carbon-sheets between which work-sheets may be readily interleaved. The mounting for the rolls is such as to permit the same carbon-sheets, or portions of the carbon-strips, to be used until worn out, whereupon fresh portions of the carbon-strips may be drawn from the rolls.

Other features and advantages will hereinafter appear.

In the accompanying drawings,

Figure 1 is a perspective view of my invention applied to a typewriting machine, only the necessary co-operating elements of the machine being shown, and the collating device being in position to permit the insertion and adjustment of work-sheets.

Figure 2 is a perspective view of an improved clamping means for the free ends of the carbon-sheets.

Figure 3 is a vertical section of the device shown in Figure 1, the collating device being shown in operative position after the work-sheets have been adjusted thereon and ready for the typing operation.

Figure 4 is an end view, showing the parts substantially as in Figure 3, but prior to the insertion of the sheets around the platen.

Figure 5 is a section taken crosswise of the carbon-strips, showing the stepped arrangement of carbon-sheets near one edge of the collating table, to facilitate the insertion of the work-sheets between the carbon-sheets.

Figure 6 is a rear elevation of the device as shown in Figures 3 and 4.

The collating device 10 comprises a collating table 11 fixed to side-rails 12, connected at their upper ends by a tie-bar 13, and supported near their lower ends on platen-axle or shaft 14 to either side of a platen 15 mounted on said axle. The platen is thus carried by the collating device, which is connected to platen-frame 20 by a linkage to be described hereinafter, and by a gear connection comprising a gear 21 fixed at each end of shaft 14 just outside of rails 12 and meshing with pinions 22 (Figures 3 and 6) supported upon shafts 23 in the end-walls 24 of the platen-frame. The gears 21, and hence the platen, are operated by rotating knobs or finger-wheels 25 fixed to shafts 26 journaled in the end-walls of the platen-frame and carrying gears 27, at their inner ends meshing with pinions 22; so that rotation of gears 27 by the finger-wheels rotates 105

110

pinions 22 and gears 21 to rotate the platen. The platen may be rotated also by the usual line-space mechanism, of which only the line-space handle 28 and ratchet-wheel 29, 5 fixed to shaft 26, are shown.

It will be seen that gears 21 can be swung out of mesh with pinions 22, and hence break the gear connection with the platen-frame. The collating device and the platen

10 which it carries are connected to the carriage by links 30 pivoted at one end by means of a rock-shaft 36 on the side-rails 12 and at the other end at 37 to lugs 31 on the carriage, and by links 32 carried at one end at 38 carried 15 by the side-rails 12 and near the other end at 39 to brackets 33 fixed to the platen-frame end-walls 19, the links 32 having ends 34 extending beyond pivot 39, and the upward movement of said ends being limited 20 by pins 35 fixed in the side-rails 12. The device is guided by the links 30 and 32 for rotary movement, and also for forward and rearward movement, so that, when the device is swung from the position shown in 25 Figure 1 to the position shown in Figure 3, the upper end thereof is swung upwardly and forwardly until the collating device is maintained in a substantially vertical position, shown in Figures 3 and 4. In this position, gears 21 mesh with pinions 22, so that 30 the platen-rotating mechanism is effective to rotate the platen, and the collating device is held firmly in position by the ends 40 of the side-rails 12 engaging in notches 41 in 35 a connecting rod 42 (Figures 3 and 6), and by the forked ends 44 of members 45 slidably mounted on the side-rails 12 engaging rod 42, the members 45 being actuated by means of a finger-piece 46.

40 The collating device, indicated generally by the numeral 10, carries carbon-rolls 47 supplying carbon-strips or sheets 48 which are fed from the rear around the platen to table 11, where work-sheets 49 are inserted 45 between the carbon-sheets while the table is in the horizontal position. The ends of the carbon-sheets are then clamped together and the table swung to vertical position to render the platen-rotating mechanism effective, and 50 the carbon-sheets and work-sheets are rotated rearwardly around the platen to the initial printing position. For this purpose, the side edges 50 of table 11 act like rails along which slide blocks 51, which support 55 a clamp 52, to be described later. Belts 53, connected to blocks 51, pass over the ends of a roller 54 mounted at the upper end of the table and around guide rollers 55, near the lower end of the table, and return to the 60 starting point at the blocks 51 to which they are fixed. At points on the belts, opposite that to which the clamp is fixed, are mounted the carbon-rolls 47, having the carbon-sheets 48 wound thereon, which are fed around the 65 platen to the table 11. The carbon-rolls are

preferably mounted on short shafts 65 and 66 between flanges 67 and 68 fixed on said shafts, shafts 65 and 66 being forced into the ends of cores 69 of said rolls. The rolls may be rotatably mounted in brackets 60 70 fixed to the belts, said brackets being connected by a bar 58 slideable upon guide-rails 59, the rolls being journaled in said brackets by short extensions of shafts 65 and 66, the shafts being laterally slideable in bearings fixed to the brackets 60 to permit shafts 65 to be withdrawn from bearings 70, so that fresh carbon-rolls may be mounted on the shafts. The rolls are normally held in their bearings by springs 71 fixed to one 80 of the brackets 60 and pressing against the rolls, said springs also preventing unwinding of the carbon-rolls during the typing operation. By holding the belts and rolls fixed and drawing on the carbon-sheets, new portions may be withdrawn therefrom when the old portions have been worn out after 85 repeated use.

The carbon-sheets are fed around the platen to the table 11, when the latter is in 90 the horizontal position shown in Figure 1, and work-sheets are inserted between the clamped carbon-sheets, the right-hand edges of which may be stepped relatively to each other to facilitate insertion of the work-sheets, Figures 1 and 5. The ends of the carbon-sheets are clamped in clamp 52 by impaling the sheets on pins 75 fixed to bar 76 of the clamp 52, said bar being supported in slides 51. The clamp is closed by an upper hinge-member 77 having openings 78, into which pins 75 project, said hinge-member catching beneath a spring-clip 79 on bar 76. The top sheet is held to the table by spring-fingers 80, fixed to the upper hinge-member 105 77. During the insertion of the work-sheets the clamp-member will be in the position shown in Figure 1, near the upper end of the collating table 11, so that the brackets 60, carrying the carbon-rolls 47, will be near 110 the lower end of the table adjacent the guide-rolls 55, and the length of the carbon-strip drawn off the rolls is the distance from the rolls around the platen to the clamp 52.

The table is then swung to the vertical position shown in Figure 4, thus rendering the platen-rotating mechanism effective. By rotating the platen rearwardly, the carbon-sheets and work-sheets are drawn rearwardly over an apron 81 (Figure 3) to the 115 hereinafter described, the clamp moving downwardly along the front of the table, and brackets 60 moving upwardly along the rear. The brackets 60 and carbon-rolls mounted thereon, act as counterweights to 120 clamp 52 to prevent said clamp from exerting a downward force at the upward ends of the carbon-sheets and work-sheets. The sheets are brought to the initial printing position, after which they are fed upwardly in 125 130

the usual manner. When the work-sheets have been typed, the carbons and work-sheets are run up on the collating table to the starting position, as in Figure 1, the 5 collating device is swung to the horizontal position, and the typed work-sheets are withdrawn; new work-sheets are then inserted between the stepped carbon-sheets. The collating device is then swung to vertical position, the carbon-sheets and work-sheets are drawn down to initial position, and the process, as described above, is repeated. It will be observed that the same 10 carbon-sheets, or portions of the carbon-rolls, are employed repeatedly until worn out, and then fresh portions may be drawn off the rolls by holding the rolls or belts in fixed position and drawing on the carbon-sheets until the desired amount is withdrawn. While the carbons have been shown and described as wound upon separate rolls, it is apparent that several layers of carbons may be wound upon the same roll.

For guiding the carbon-sheets and work-sheets around the platen, there is provided the apron 81, having an upward and rearward extension forming a paper shelf 83. Springs 82 are connected to the upper end of said shelf and to the adjacent side-rails 30 to hold feed rolls 84, fixed to the under side of the apron and projecting therethrough, in contact with the platen. To release the apron and rolls to permit the insertion of sheets from the front, links 86, pivoted to 35 the shelf and the adjacent side-rails, are provided, and are operable to force the apron downwardly against the action of springs 82 by means of a handle 87 fixed to operating cams 88 and operating in slots 40 89 in links 86. The apron is supported also by rod 90, to the ends of which are fastened links 91 pivoted on side-rails, said links being adjustable lengthwise by means of lock-nuts 92 to vary the distance of the apron 45 from the platen.

Variations may be resorted to within the scope of the invention, and portions of the improvements may be used without others.

Having thus described my invention, I 50 claim:

1. In a typewriting machine, in combination, a platen-frame having a platen journaled therein, a collating device mounted at the front of the platen and comprising a 55 collating table, and a carbon-roll mounted for reciprocatory movement on said device, said roll supplying carbon-sheets to be fed around said platen to said collating table, said carbon-roll moving downwardly on said device as said sheets are fed around said platen and upwardly on said table.

2. In a typewriting machine, in combination, a platen-frame having a platen journaled therein, a collating device mounted 60 at the front of the platen and comprising

a collating table, and a carbon-roll mounted for reciprocatory movement on said device, said roll supplying carbon-sheets to be fed around said platen to said collating table, said carbon-roll moving lengthwise 70 of said device as said sheets are fed around said platen to said collating table.

3. In a typewriting machine, in combination, a platen-frame having a platen journaled therein, a collating device mounted at 75 the front of the platen and comprising a collating table, and carbon-rolls mounted for reciprocatory movement on said device, said rolls supplying carbon-sheets to be fed around said platen to said collating table, 80 said carbon-rolls moving downwardly on said device as said sheets are fed around said platen and upwardly on said table.

4. In a typewriting machine, in combination, a platen-frame, a collating device 85 pivotally mounted on said frame and comprising a collating table, a platen movable with said device, a carbon-roll mounted for reciprocatory movement on said collating device, said carbon-roll supplying carbon- 90 sheets to be fed around said platen to said collating table, said carbon-roll moving downwardly on said device as said sheets are fed around said platen and upwardly on said table, and means for holding said carbon-roll against unwinding.

5. In a typewriting machine, in combination, a platen-frame, a collating device pivotally mounted on said frame and comprising a collating table, a platen movable 100 with said device, a carbon-roll mounted for reciprocatory movement on said collating device, said carbon-roll supplying carbon-sheets to be fed around said platen to said collating table, said carbon-roll moving 105 downwardly on said device as said sheets are fed around said platen and upwardly on said table, and friction means for holding said carbon-roll against unwinding, said friction means being overcome by drawing 110 on said carbon-sheets when it is desired to withdraw a fresh carbon-sheet from said roll.

6. In a typewriting machine, in combination, a platen-frame, a collating device pivotally mounted on said frame and comprising a collating table, a platen movable with said device, carbon-rolls mounted for reciprocatory movement on said collating device at the rear thereof, said carbon-rolls 115 supplying carbon-sheets to be fed around said platen to said collating table, said carbon-rolls moving downwardly on said device as said sheets are fed around said platen and upwardly on said table, and means for holding 120 said carbon-rolls against unwinding.

7. In a typewriting machine, in combination, a platen-frame, a collating device pivotally mounted on said frame and comprising a collating table, a platen movable with said 130

device, carbon-rolls mounted for reciprocatory movement on said collating device at the rear thereof, said carbon-rolls supplying carbon-sheets to be fed around said platen 5 to said collating table, said carbon-rolls moving downwardly on said device as said sheets are fed around said platen and upwardly on said table, and friction means for holding each of said carbon-rolls 10 against unwinding, said friction means being overcome by drawing on said carbon-sheets when it is desired to withdraw fresh carbon-sheets from said rolls.

8. In a typewriting machine, in combination, a platen-frame having a platen journaled therein, a collating device mounted at the front of the platen and comprising a collating table, belts mounted on said collating device one at each side for movement lengthwise thereof, and a carbon-roll 20 fixed to said belts and movable therewith, said carbon-roll supplying carbon-sheets to be fed around said platen to said collating table, said carbon-roll moving downwardly 25 along said device as said sheets are fed around said platen and upwardly on said table.

9. In a typewriting machine, in combination, a platen-frame having a platen journaled therein, a collating device mounted at the front of the platen and comprising a collating table, belts mounted on said collating device one at each side for movement lengthwise thereof, and carbon-rolls 35 fixed to said belts and movable therewith, said carbon-rolls supplying carbon-sheets to be fed around said platen to said collating table, said carbon-rolls moving downwardly along said device as said sheets are fed 40 around said platen and upwardly on said table.

10. In a typewriting machine, in combination, a platen-frame having a platen journaled therein, a collating device mounted 45 at the front of the platen and comprising a collating table, belts mounted on said collating device one at each side for movement lengthwise thereof, a carbon-roll fixed to said belts and movable therewith, and a 50 clamp fixed to said belts and movable therewith along said collating table, said clamp and carbon-roll moving in opposite directions, said carbon-roll supplying carbon-sheets to be fed around said platen to said 55 collating table, the front ends of said carbon-sheets being held by said clamp, said carbon-roll moving downwardly along said device as said sheets and clamp move upwardly on said collating table, and a friction connection between said brackets 60 and said carbon-rolls for holding said rolls against unwinding.

11. In a typewriting machine, in combination, a platen-frame having a platen journaled therein, a collating device mounted at the front of the platen and comprising a collating table, belts mounted on said 65 collating device one at each side for move-

ment lengthwise thereof, said belts having front and rear portions movable in opposite directions, a carbon-roll fixed at the rear of said collating device to the rear of said belts and movable therewith, and a 70 clamp fixed to said belts at the front thereof and movable therewith, said clamp and carbon-roll moving in opposite directions, said carbon-roll supplying carbon-sheets to be fed around said platen to said collating 75 table, the front ends of said carbon-sheets being held by said clamp, said carbon-roll moving downwardly along said device as said sheets and clamp move upwardly on said collating table.

12. In a typewriting machine, in combination, a platen-frame having a platen journaled therein, a collating device mounted at the front of the platen and comprising a collating table, belts mounted on said collating device one at each side for movement lengthwise thereof, brackets fixed to said belts at the rear thereof and movable therewith, carbon-rolls mounted in said brackets at the rear of the collating device, said carbon-rolls supplying carbon-sheets to be fed around said platen to said collating table, and a clamp fixed to said belts at the front thereof and movable therewith along said collating table, the front ends of said carbon-sheets being held by said clamp, said brackets and carbon-rolls moving downwardly along said device as said sheets and clamp move upwardly on said collating table.

13. In a typewriting machine, in combination, a platen-frame having a platen journaled therein, a collating device mounted at the front of the platen and comprising a collating table, belts mounted on said collating device one at each side for movement lengthwise thereof, brackets fixed to said belts at the rear thereof and movable therewith, carbon-rolls mounted in said brackets at the rear of the collating device, said carbon-rolls supplying carbon-sheets to be fed around said platen to said collating table, a clamp fixed to said belts at the front thereof and movable therewith along said collating-table, the front ends of said carbon-sheets being held by said clamp, said brackets and carbon-rolls moving downwardly along said device as said sheets and clamp move upwardly on said collating table, and a friction connection between said brackets 110 and said carbon-rolls for holding said rolls against unwinding.

14. In a typewriting machine, in combination, a platen-frame having a platen journaled therein, a collating device mounted at the front of the platen and comprising a collating table, belts mounted on said collating device one at each side for movement lengthwise thereof, brackets fixed to said belts at the rear thereof and movable 125

therewith, carbon-rolls mounted in said brackets at the rear of the collating device, said carbon-rolls supplying carbon-sheets to be fed around said platen to said collating table, a clamp fixed to said belts at the front thereof and movable therewith along said collating table, the front ends of said carbon-sheets being held by said clamp, said brackets and carbon-rolls moving downwardly along said device as said sheets and clamp move upwardly on said collating ta-

ble, and a friction connection between said brackets and said carbon-rolls for holding said rolls against unwinding, said friction connection being overcome by drawing on 15 said carbon-sheets when it is desired to withdraw fresh carbon-sheets from said rolls.

JOHN A. WHERRY.
